UNITED STATES PATENT OFFICE.

WARREN W. COLE, OF PORTLAND, MAINE.

METAL SCREEN.

1,396,164.

Specification of Letters Patent.

Patented Nov. 8, 1921.

Application filed November 30, 1917. Serial No. 204,705.

To all whom it may concern:

Be it known that I, WARREN W. COLE, a citizen of the United States, and resident of Portland, county of Cumberland, State of Maine, have invented an Improvement in Metal Screens, of which the following description, in connection with the accompanying drawings, is a specification, like characters on the drawings representing like parts in each of the several views.

This invention relates to window screens of the type adapted to be slidably fitted to guides for use at the upper or lower sash of a window. More particularly the invention has to do with a screen of this type having a solid metal frame with guide ribs at its sides fitting into grooves of molding members preferably of wood adapted to be fixed to the window frame at the sides of the window opening. Such a construction presents marked advantages as compared with either a wood frame screen, or with a hollow metal frame screen in respects that will be better understood from the following detailed description taken in connection with the accompanying drawings and the distinctive features of novelty will therefore be pointed out in the appended claims.

Referring to the drawings:

30 Figure 1 is a front elevation showing a screen constructed in accordance with my invention applied to a window;

Fig. 2 is a partial transverse sectional view showing the manner of fitting this 35 screen with respect to the window sash;

Fig. 3 is a partial front elevation showing a portion of the screen removed from the window;

Fig. 4 is an edge view of the screen portion seen in Fig. 3;

Fig. 5 is a partial plan view of the screen portion seen in Fig. 3; and

Fig. 6 is a plan view of the screen with the molding guides in section and with an 45 intermediate portion of the screen broken away.

An ordinary window frame is indicated at 10 with usual upper and lower sliding sashes 11, 12 respectively. The screen of my invention consists in a solid metal frame 13 produced in any suitable manner as by electric welding the corners, so that the frame is made into a unitary mass of metal all the way around. The wire mesh 14 may be secured to the frame by soldering or in any 55 other suitable way. In accordance with my

invention the sides of the frame 13 are rabbeted to form central guide ribs 15 which project out some little distance from the opposite sides of the frame. The rabbeted 60 edge of the frame on one side is equipped with bow springs 16 riveted or otherwise fixed thereto as seen at 17, these springs being located at each side of the rib 15 which is shown as reduced in thickness along this 65 part thereof as seen at 18 so that said springs may be of greater width and still lie wholly within the planes of the sides of the frame. The ribs 15 are adapted to fit into the grooves of molding strips 19, 20 preferably 70 of wood, and fixed at the sides of the window frame. These molding strips have the grooves therein so formed that the inside lip 21 of the molding is of a thickness to permit the screen to be closely fitted against the bottom of the upper window sash as seen at 22, thereby preventing the entrance of insects. The groove 19^a in the molding piece 19 is relatively shallow while the groove 20^a in the molding piece 20 is much deeper, this 75 being the side at which the springs 16 are located, thus permitting the screen to be easily taken out and replaced by moving it to compress the springs 16 and remove the rib 15 at the left, as shown, from the shallow groove 19^a. A suitable lift 23 may be fixed centrally of the bottom of the screen frame affording a convenient hand hold.

Among the advantages to be noted for the present construction are that with the 90 metal screen running in slide ways formed by wood molding it can be readily made to fit window frames presenting some little irregularities by merely planing the back of the molding strips, which to permit this are 95 preferably made initially some little thicker than necessary. It is to be observed that even if these molding strips are of relatively thick stock, since the screen frame itself is relatively narrow, the window opening is 100 not reduced materially by the screen. Likewise if a screen is too tight in its guides the back and side can be planed enough so as to make the guide yielding to the requisite degree, or if the screen is too loose a slightly 105 wider or thicker guide can be employed. With the use of the grooved molding guides, the groove 20^a at the side where the springs 16 are located may be made relatively deep and the metallic tongue or rib 15 correspondingly wide so that the screen frame will 110 co-operate properly with the molding guides

and continue easily operative therein even though the molding guides may develop more or less irregularity from shrinkage or other distortion of the window frame, it 5 being of course possible to make the ribs 15 wider in metal, than they could be made in wood without rendering them liable to split off or become damaged. The springs 16 being exposed on the face of the screen frame 10 can be readily finished, and are accessible for attention, as for wiping off when necessary, whereas with the springs housed in the grooves of the frame as usual in previous constructions they are difficult to reach for 15 any attention that may be necessary. Further advantages of the use of the wood molding guide pieces are that they are substantial and do not bend easily, so that the metal screen frame will always slide readily therein, and having no sharp corners they are not 20 apt to tear lace curtains or the like which might blow out of the window, or lacerate the hands of one having occasion to reach through the window as for washing the 25 same. The screen frame itself being of solid metal avoids a tendency to accumulate moisture within itself such as to cause oxidation or rust as would be the case with a hollow metal frame or with a wood frame. The 30 solid metal construction also presents the same strength with a great deal less stock as to bulk of the frame than would a hollow frame and hardly at all obstructs the field of vision through the window. I am aware 35 that the invention may be embodied in other specific forms without departing from the spirit or essential attributes thereof, and I therefore desire the present embodiment to

be considered in all respects as illustrative and not restrictive, reference being had to 40 the appended claims rather than to the foregoing description to indicate the scope of the invention.

Having described my invention, what I claim as new and desire to secure by Letters 45 Patent is:

1. A screen as described, with a solid and unitary metal frame rabbeted at its sides to form relatively thin and wide projecting guide ribs, springs fitted to such rabbeted sides, and wood molding members adapted to be secured to the sides of the window frame and having grooves therein to receive 50 said ribs.

2. A screen as described, comprising a solid metal frame composed of a unitary mass of metal rabbeted at its sides and presenting projecting guide ribs with springs mounted laterally of such ribs, and rails of 55 wood presenting plain back adapted to be planed for fitting to sides of a window frame, said rails having grooves in the inner sides thereof to receive 60 said ribs.

3. A screen as described, comprising a solid one-piece metal frame rabbeted at its 65 sides and presenting relatively wide and thin transversely central guide ribs with springs mounted at the sides of such ribs, and rails of wood presenting relatively thick plain backs adapted to be planed for fitting two 70 sides of a window frame, said rails having grooves in the inner sides thereof to receive the ribs.

In testimony whereof, I have signed my name to this specification.

WARREN W. COLE.
